DESIGN.

T. & G. M. STONE.

METAL PLATE.

No. 18,581.

Patented Aug. 28, 1888.

UNITED STATES PATENT OFFICE.

THOMAS STONE AND GEORGE M. STONE, OF NEWARK, NEW JERSEY, ASSIGNS TO HALL & CARPENTER, OF PHILADELPHIA, PENNSYLVANIA.

DESIGN FOR A METAL PLATE.

SPECIFICATION forming part of Design No. 18,581, dated August 28, 1888.

Application filed June 27, 1888. Serial No. 218,350. Term of patent 7 years.

To all whom it may concern:

Be it known that we, THOMAS STONE and GEORGE M. STONE, citizens of the United States, residing at Newark, in the county of Essex, State of New Jersey, have invented and produced a new and original Design for Sheet-Metal Plates, of which the following is a specification, reference being had to the accompanying photograph, forming part thereof.

The leading features of our design for a sheet-metal plate are the representations of a vase and tea-pot with fans and umbrellas grouped around the same, and, next, of butterflies, birds, fruits, and flowers interspersed among said parts.

On the face is the representation of a vase, 1, and of a tea-pot, 2. Grouped around said

vase and teapot is the representation of umbrellas 3 and fans 4. Interspersed among the several parts 1, 2, 3, and 4 are representations of butterflies 5, birds 6, fruit 7, and flowers 8. The background is dotted or picked.

We claim—

The design for a sheet-metal plate having on its face the representation of a vase and pot with umbrellas and fans grouped around the same, interspersed with representations of butterflies, birds, fruits, and flowers, as shown and described.

THOMAS STONE.
GEO. M. STONE.
